W. L. CALDWELL.
INTAKE MANIFOLD HEATER.
APPLICATION FILED MAR. 11, 1918.

1,304,738.

Patented May 27, 1919.

UNITED STATES PATENT OFFICE.

WILLIAM L. CALDWELL, OF INDIANAPOLIS, INDIANA.

INTAKE-MANIFOLD HEATER.

1,304,738.

Specification of Letters Patent. Patented May 27, 1919.

Application filed March 11, 1918. Serial No. 221,738.

To all whom it may concern:

Be it known that I, WILLIAM L. CALDWELL, a citizen of the United States, residing at Indianapolis, in the county of Marion 5 and State of Indiana, have invented certain new and useful Improvements in Intake-Manifold Heaters; and I do declare the following to be a full, clear, and exact description of the invention, such as will enable 10 others skilled in the art to which it appertains to make and use the same.

My invention has for one object to provide an extremely simple and inexpensive, yet a highly efficient and durable device for 15 heating the intake manifold of internal combustion engines, particularly automobile engines, to insure easy starting in cold weather.

A further object is to so construct the device as to cause it to force radiation of heat 20 from the exhaust manifold onto the intake manifold when the engine is running under its own power, thus more readily vaporizing the fuel and giving better results.

With the foregoing general objects in 25 view, the invention resides in the novel features of construction and unique combinations of parts to be hereinafter fully described and claimed, the descriptive matter 30 being supplemented by the accompanying drawings which form a part of the specification and in which:

Figure 1 is a side elevation of an automobile engine showing the application of the 35 invention;

Fig. 2 is a vertical transverse section on the plane of the line 2—2 of Fig. 1;

Fig. 3 is a perspective view illustrating the outer side of the heater; and

Fig. 4 is a similar view showing the inner side of the device.

Briefly speaking the invention comprises a casing 1 adapted to contain a torch and having an open side for directing the flames 45 from the torch onto the center of the intake manifold I, together with a suspending plate 2 for said casing, the upper edge portion of said plate being bent laterally and downwardly at 3 to form an arched hood for 50 passage over the exhaust manifold E. The inner side of the aforesaid hood is provided with a layer of insulating material such as asbestos as indicated at 4, this layer serving to prevent upward radiation of heat from 55 the exhaust manifold E when the engine is

in operation, with the result that all heat will be radiated downwardly from said manifold onto the adjacent portion of the intake manifold I. This highly heats the intake and insures more thorough vaporization of the fuel, with the result that more perfect combustion will take place in the engine cylinders. The front end of the hood is preferably closed by bending the sheet metal from which it is constructed inwardly 60 and riveting as shown at 5 in Figs. 3 and 4.

The casing 1 is preferably of the sheet metal construction shown, comprising a rectangular outer side or body 6, a top 7 bent laterally from the upper end of the side 6 70 and then bent upwardly to form a flange 8, a bottom 9 bent laterally from the lower end of the side 6 and further bent upwardly to partially close the inner side of the casing, and a pair of additional side walls 11 75 bent laterally from the vertical edges of the side 6, the upper ends of said sides 11 being bent laterally into overlapping relation as shown at 12 and riveted together and to the top 7 as disclosed at 13, while the lower ends 80 of the walls 11 are bent inwardly and seamed together as illustrated at 14. The flange 8 above described is secured by a bolt or the like 15 to the lower edge portion of the plate 2 and said edge is formed with 85 a pair of notches 16 into which the upper corners of the side walls 11 project, the metal between said notches being bent laterally under the top 7 of the casing 1 as indicated at 17. This construction prevents 90 tilting of the casing in respect to the plate 2 even though only a single fastener 15 be employed. The lower edge of plate 2 is provided with additional notches 18 to receive the manifold clamp studs 19 of the 95 engine as shown in Fig. 1, and the portions 20 of the metal between the several notches are adapted to be clamped under the manifold clamps 21, thereby to secure the entire device rigidly in place.

In operation, a torch T is saturated with wood alcohol or other suitable fuel and either before or after lighting this torch, it is inserted into the casing 1 through a suitable opening 22 in one side thereof. The 105 flames and heat from the torch are thrown against the intake manifold I and heat the latter amply to insure easy starting in the coldest weather. While the engine is running under its own power, the hood 3 and 110

its asbestos lining 4 prevent the upward radiation of heat from the exhaust manifold E, with the result that downward radiation of such heat is forced, thus highly 5 heating the manifold I and insuring more thorough vaporization of the fuel than is otherwise possible.

From the foregoing, taken in connection with the accompanying drawing, it will be 10 obvious that although my invention is of extremely simple and inexpensive nature, it will be highly efficient for the purposes intended. Since probably the best results 15 are obtained from the sheet metal construction shown and described, such construction is by preference employed, but within the scope of the invention as claimed, numerous minor changes may well be made.

I claim:

An intake manifold heater comprising a 20 casing adapted to contain a torch and having an open side for directing the flame therefrom against the intake manifold, and a suspension plate for said casing extending upwardly therefrom and curved laterally 25 and downwardly to form an arched hood for passage over the exhaust manifold, said hood being of substantially the same length as the horizontal portion of the intake manifold and being insulated to increase the 30 downward radiation of heat from the exhaust manifold.

In testimony whereof I have hereunto set my hand.

WILLIAM L. CALDWELL.
